EXTENSIBLE HASP AND HINGE FITTING

Charles William Cheney, Soho,
Birmingham, EnglandApplication August 25, 1934, Serial No. 741,428
In Great Britain August 29, 1933

1 Claim. (Cl. 292—281)

This invention relates to extensible hasp and hinge fastenings for luggage such as attaché and suit cases and trunks of variable capacity in which the lid can telescope over the body of the case or trunk to collapse it or extend it, dependent upon the contents thereof.

The invention more particularly relates to extensible fastenings of the type embodying an elongated casing provided with a line of ratchet teeth, an elongated slide telescopically fitting the casing and a hasp or flap hinged to the outer end of the slide, there being provided a ratchet action between the slide and the casing to be automatically released when the hinged hasp or flap is moved into a certain position. In practical use the ratchet action becomes operative when the hinged member of the fastenings is closed when the lid of the luggage can be further collapsed but not extended, whereas the ratchet action becomes automatically inoperative when said hinged member opens.

In fittings of this type as at present constructed, there is the disadvantage that the pawl of the ratchet action accidentally slips out of engagement with the ratchet teeth due to the necessary loose fitting of the slide in the casing. This drawback mainly arises through the following condition:—When the nose of the pawl engages the ratchet teeth strain tending to extend the fastenings exerts a tension on the pawl between its engaging nose and its point of pivot with the result that any slight wobble of the slide in the casing will cause slip in the ratchet action when the fastenings become inefficient and the lid insecurely connected to the body.

The object of this invention is to provide for a more effective operation of the pawl on the ratchet teeth so that when the lid has been telescopically adjusted with respect to the body the adjusted position will be permanently retained until the fastenings are released, and the invention consists in a combination and arrangement of parts of which the essential feature resides in the pawl being carried by the slide at the inner end thereof and being operative with the ratchet teeth in such a manner that strain tending to extend the fastenings intensifies the pressure of the pawl engaging the teeth, the pawl being in compressive action between its nose and its point of pivoting.

Said combination will now be more particularly described with reference to the explanatory drawing and the features of novelty will be hereinafter specifically claimed.

Fig. 1 is a vertical sectional elevation of an

extensible hasp lock fastening applied to a trunk, sufficient of which is shown for illustrative purposes.

Fig. 2 is a vertical sectional elevation of the extensible hasp fastening with the hasp in open position so that the elements can telescope without the ratchet action.

Fig. 3 is a vertical section of Fig. 2 taken on the dotted lines A—A.

Fig. 4 is a fragmentary sectional elevation of the invention applied to an extensible hinge applied to a trunk.

Fig. 5 is a vertical sectional elevation, with the elements in position similar to Fig. 2, of a modified form of invention.

Fig. 6 is a back view of a further modification.

Fig. 7 is a perspective view of the pawl employed in Figs. 1—5.

Where possible, similar numerals of reference denote corresponding parts throughout the several views.

Referring to Figs. 1—4, the lid 1 telescopically fits over the body 2 of a trunk of variable capacity.

The extensible fastenings for the trunk comprise usually a pair of hinges and a pair of hasp lock fastenings.

The hasp lock fastenings comprise an elongated sheet metal casing 3 closed at its upper end and having a back plate 4 from which is raised a central line of strong ratchet teeth 5, the back plate being assembled to the casing by eyelets applied through openings 6 in side lugs 7 which provide means for attaching the casing 3 to the lid 1. The lower open end of the casing 3 receives a trough shaped elongated slide 8 to the lower end of which a hasp 9 is hinged by the pin 10. The torsionally operating spring 11 ensures that the hasp normally occupies the position shown at Fig. 2 so that when its staple 12 eye 12 is released from the bolt of the lock 13, in the usual manner, it will have a fly-off action, this feature being customary with hasp lock fastenings. Disposed within the slide 8 is a first-order lever 14 of sheet metal and which is fulcrumed to the slide so as to be rockable longitudinally thereof by opposite integral pintles 15 engaging openings in the opposite side walls 16 of the slide.

On the inner end of the slide 8 adjacent the inner end of the lever 14 is a pawl 17 pivoted adjacent the ratchet teeth 5 by a transversely directed pin 18 whose ends are located in the opposite walls 16 of the slide.

As will be seen from Fig. 7 the pawl is formed

from a sheet metal blank and provides a pawl nose 19, hinge barrels 20 and an operating plate portion 21, all integrally formed.

Surrounding the pivot pin 18 is a torsionally operating spring 22 of less strength than the spring 11 associated with the hinged hasp, said spring 22 normally pressing the pawl nose 19 into engagement with the central line of ratchet teeth 5.

10 The inner end of the lever 14 lies within the path of the plate portion 21 of the pawl and the lower end of said lever is adapted to be operated upon by a cam 23 formed as an integral upper extension of the hasp 9, the cam 23 moving within 15 the lower open end of the slide 8 and being guided by the shaped portion 24 thereof.

In the position of the hasp in Fig. 2 the cam 23 thereof has positively rocked the lever 14 whose inner end transmits pivotal movement to 20 the pawl and causes its nose 19 to disengage the ratchet teeth 5 against the action of its associated spring 22. In this position the slide 8 can telescope within the casing 3, the ratchet action 25 being inoperative.

25 When the hasp is moved into fastening position with the bolt of the lock 13 as illustrated at Fig. 1, the cam 23 has moved away from the lower end of the lever 14 and the power of the pawl spring 22 presses the nose 19 into frictional 30 engagement with the ratchet teeth and simultaneously moves the lever away. In this position the lid of the case can be further collapsed but cannot be extended and strain upon the extensible fittings tending to produce an extension between 35 the casing 3 and the slide 8 will intensify the pressure that the pawl nose 19 exerts upon the teeth 5, because the pawl is pivoted at the upper end of the slide and the strain produced by extending forces between the elements of the 40 fastenings places the pawl in a state of compression between its nose and its point of pivoting.

In Fig. 4, which illustrates a hinge fastening, the lower end of the slide 8 has an attachment 45 plate or flap 25 hingedly connected thereto instead of the hasp shown in Figs. 1-3. The attachment plate 25 also includes a nose 26 on which the case is adapted to rest when the flap is applied to the back of the body 2 of the 50 collapsible trunk.

Referring to Fig. 5 which embodies the essentials of the invention, the hasp fastening is modified by the coupling means interposed between the cam of the hasp 9 and the pawl. The modification consists in the employment of a slidable link 26, mounted within the slide in guides 27 shaped out of the metal thereof, and the inner end of said link is inclined at 28 and is forked 55 so as to bear against the plate surface 21 of the pawl illustrated at Fig. 7. The lower end of the

link 26 is reduced in width to form a T shape which lies within a slot 29 formed in the cam 23 of the hasp with the head of the T engaging the lower face of cam 23. Thus, when the hasp is in the released or unfastened position 5 as illustrated the link 26 is positively slid upwardly by the slotted cam so that its inclined end 28 positively moves the nose 19 of the pawl 10 out of engagement with the ratchet teeth 5, whereas when the hasp 9 is moved into the fastening position to be engaged by the bolt of the lock as in Fig. 1, the force of the pawl spring 22 moves the link 26 downwardly so that the pawl engages the ratchet teeth in the manner hereinbefore explained, and any strain between 15 the slide 8 and the casing 3 tending to extend the fastenings intensifies the pressure with which the pawl engages the ratchet teeth.

With reference to Fig. 6, a lever 14 is employed as a means for the automatic operation of the 20 pawl through the cam 23 of the hasp 9. In this example, the lever 14 is fulcrumed at 30 to the face of the slide 8 so as to rock transversely thereof and a pawl 31 is pivoted by the pin 32 on the upper end of the lever and operated upon 25 by the torsional spring 22. The cam 23 at the inner end of the hasp is in the form of a horn or heel and operates upon the outer end of the lever. In the position of the parts as illustrated, the hasp 9 is in the fly-off or open position as 30 indicated previously by Figs. 2, 3, and 5, the horn 23 having positively rocked the lever 14 and its pawl out of engagement with the ratchet teeth 5. In the reverse position of the hasp the power 35 of the torsional spring 22 associated with the pawl rocks the lever 14 into a position where the pawl is pressed into engagement with the teeth 5 and the same conditions prevail when strain is applied between the slide 8 and the casing 3 as hereinbefore set forth.

Having now described my invention, what I 40 claim and desire to secure by Letters Patent is:—

Extensible hasp and hinge fittings comprising in combination an elongated casing provided with a line of ratchet teeth, an elongated hollow 45 slide telescopically fitting the casing, a coupling member movably mounted in the slide and consisting of a first order lever fulcrumed transversely to the slide and rockable longitudinally thereof, a spring pressed pawl mounted on the 50 slide so as to move therewith and pivoted in relation to the ratchet teeth so that strain tending to extend the fittings further presses the pawl into engagement with the teeth, a member hinged at the outer end of the slide, and a cam 55 provided on the hinged member and adapted to operate on the coupling lever to control the action of the pawl.

CHARLES WILLIAM CHENEY. 60
